UNITED STATES PATENT OFFICE.

EDWARD J. HOFFMAN, OF SIOUX CITY, IOWA, ASSIGNOR OF TWO-THIRDS
TO WILLIAM H. FREED, OF SAME PLACE, AND WILLIAM H. RANSOM, OF
MISSOURI VALLEY, IOWA.

PREVENTING INCrustATION IN STEAM-BOILERS.

SPECIFICATION forming part of Letters Patent No. 298,172, dated February 5, 1884.

Application filed June 16, 1883. (No model.)

To all whom it may concern:

Be it known that I, EDWARD J. HOFFMAN, of Sioux City, in the county of Woodbury and State of Iowa, have invented certain new and useful Improvements in Devices for Preventing Incrustation in Steam-Boilers; and I do hereby declare that the following is a full, clear, and exact description of the invention, which will enable others skilled in the art to 5 which it appertains to make and use the same, reference being had to the accompanying drawings, which form a part of this specification, and in which—

Figure 1 is a perspective view of my improved device or apparatus for preventing incrustation of or the forming of sediment in steam-boilers. Fig. 2 is a similar view of the same with one of its heads removed. Fig. 3 is a longitudinal sectional view, and Fig. 4 is 10 a cross-section.

Similar letters of reference indicate corresponding parts in all the figures.

My invention has relation to devices for preventing the incrustation of steam-boilers; and 15 it consists in the peculiar construction of a receptacle adapted to contain a cement or composition which, when dissolved in the boiler, will effectually prevent incrustation of the same.

20 The object of my invention is to construct a receptacle which, while more especially adapted for the boilers of locomotives, may be used with any other kind of steam-boiler, and by the use of which there will be no waste 25 in the use of the compound or composition. As to the nature or manner of compounding this composition, I do not limit myself to any particular kind, my present invention having relation solely to the construction of the receptacle adapted to contain the compound or composition, and to feed the same gradually 30 to the water in the boiler in the proportion in which it may be required.

In the accompanying drawings, A is a casing or receptacle in the shape of a cylinder, or it may be oval in cross-section, so that it may readily be inserted into the boiler through one of the hand-holes. The interior of this casing is divided by three diaphragms, B B B,

5 into a central chamber, C, and three outer chambers, D D D, the cross-section for each of which presents in shape (when the casing is cylindrical in shape, as on the drawings) the segment of a circle, while the central chamber, C, is triangular in cross-section. Inserted through the central chamber or compartment, C, is a coiled spring, E, the straight ends e of which project out through central apertures, F, in the heads G of the casing or receptacle A. Inserted through each of the 10 outside chambers or compartments, D, are twisted wires H, the ends of which similarly project through apertures h in the heads G. The central compartment, C, communicates with the outer compartments, D, by notches 15 or apertures e, cut in the diaphragms B, as shown more clearly in Fig. 2 of the drawings. The anti-incrusting compound or composition is poured into the compartments C and D D D, where it will soon harden around the 20 central spring, E, and twisted wires H in their respective compartments. The receptacle containing the compound being placed 25 in the boiler, its contents will be gradually dissolved and fed by the ends of the coiled 30 spring E and by the projecting ends of the twisted wires H through the apertures F and h in such quantities as to effectually answer 35 the result without unnecessary waste of material.

Having thus described my invention, I claim and desire to secure by Letters Patent of the 40 United States—

1. A case or receptacle adapted to contain compound or composition for preventing incrustation of steam-boilers, consisting of a closed casing of suitable shape containing one or more inside chambers or compartments adapted to contain the compound, and provided with wires having their ends projecting 45 through apertures in the heads of the casing, and adapted to feed the contents of the same gradually through the apertures, substantially 50 as and for the purpose shown and set forth.

2. The apparatus for preventing incrustation of steam-boilers, consisting of a box or casing, A, of suitable shape, divided longitudinally by diaphragms B into a central com-

partment, C, and outside compartments, D, and provided with the coiled spring E and twisted wires H, projecting out through apertures in the heads of the casing or receptacle, constructed and combined substantially as and for the purpose herein shown and set forth.

In testimony that I claim the foregoing as my own I have hereunto affixed my signature in presence of two witnesses.

EDWARD J. HOFFMAN.
